UNITED STATES PATENT OFFICE.

EUGENE BERNINGHAUS, OF CINCINNATI, OHIO.

HEADREST APPARATUS.

Application filed April 21, 1923. Serial No. 633,747.

To all whom it may concern:

Be it known that I, EUGENE BERNINGHAUS, a citizen of the United States, residing at Cincinnati, in the county of Hamilton and State of Ohio, have invented certain new and useful Improvements in Headrest Apparatus, of which the following is a specification.

My invention relates to improvements in head-rest for barber, surgical and similar chairs. One of its objects is to provide a more simple, reliable and inexpensive apparatus by means of which the head-rest may be supported, and readily and conveniently adjusted with reference to the back of a chair and satisfactorily applied to the variety of uses for which it may be required. Another object is to provide a firm rigid reliable apparatus adapted to be employed with confidence to support the head during the performance of operations upon the eye or other portions of the head. Another object is to provide an improved combination of head-rest supporting and adjusting apparatus. My invention also comprises certain details of form combination and arrangement, all of which will be fully set forth in the description of the accompanying drawings, in which:

Fig. 1, is a side elevation partly in section of a head-rest embodying my improvements.

Fig. 2, is a plan of the head-rest shown in Fig. 1.

Fig. 3, is a plan of the upper slotted adjusting member detached.

Fig. 4 is a plan of the middle slotted adjusting member detached.

Fig. 5 is a bottom plan of the lower slotted adjusting member detached.

Fig. 6 is perspective view of a guide-bolt detached.

The accompanying drawings illustrate the preferred embodiment of my invention in which 15 represents the back of a chair, as for instance the adjustable back of a surgical, barber, optometrist's or similar chair. A plate 16 is rigidly attached to the rear of said chair back and is preferably provided with two perforated projections 17 and 18, each provided with a set-screw 19, by means of which the shank 20 of a head-rest may be firmly clamped to the chair back at two places if desired to afford a more than usually firm and reliable adjustable attachment of the head-rest shank to the chair back.

At the upper-end of the shank 20 is rigidly attached a slotted cross-bar or adjusting member 21 having a slot 22 longitudinally thereof. The slot 22 is preferably countersunk or recessed at its lower face to provide a guideway 24 to receive and act as a channel and guide way for the head 25 of a bolt 26. Mounted above and resting upon the upper substantially plane face of the cross-bar 21 is a slotted adjusting member 27, which is slidably adjustable upon the cross-bar 21. The member 27 is slotted at 23 at one end and provided with a pair of ears 28 to which the head-rest block 29 is pivotally attached by means of a pivot pin 30. The adjusting member 27 is also provided with a slot 31 longitudinally thereof which is designed to register with and lie vertically above the slot 22 in the cross-bar 21. The slot 31 is longer however than the slot 22, to provide for a considerable range of adjustment of the member 27 upon and relative to the cross-bar 21.

Vertically above the slotted adjusting member 27 is a slotted adjusting member 32, which is provided with a slot 33 and a pair of ears 34 at one end, and with a slot 35 longitudinally thereof to register with and lie vertically above the slots 22 and 31. The slot 35 is shorter than the slot 31. A hand actuated guiding and clamping bolt 36 passes downwardly through a collar 37, and through the slots 35 and 31, and its lower end is threaded into the extended end of the cross-bar 21. The clamping and guide bolt 36 has a rectangular head 25 which rests in and is guided along the recess 24, which recess also prevents the head of the bolt from being turned. The main section of the shank of the bolt 26 passes through the slots 31 and 35 which slots act as guides along which the shank of said bolt 26 is adjustable. The reduced end 38 of the bolt 26 is threaded and is screwed into a threaded recess 39 in the adjusting member 32 until the shoulder 40 of the bolt 26 seats firmly against the under face of member 32. The length of the main shank of bolt 26 is such as to hold the members 21, 27, and 32 against displacement relatively, and at the same time to enable said members 21, 27, and 32 to slide freely one upon the other. The clamping bolt 36 acts similarly near the opposite ends of the slots 31 and 35 to hold the members 21, 27 and 32 in relative position and to guide said members endwise of

said slots 22, 31 and 35, and when the members 21, 27, and 32 have been adjusted to the desired relative positions, to at a single operation clamp all of said members rigidly 5 to their adjusted position by tightening up on the bolt 36, to thereby hold the head-rest to any position to which it may have been adjusted.

The head-rest block 29 is provided with 10 a yoke 42 to which yoke are attached a pair of upholstered head-rest pads 43 and 44, to directly contact with and support the head of a person occupying the chair. The head-rest block 29 is pivotally connected by 15 means of a pivot pin 45 with one end of a link 46. The opposite end of said link 46 enters the slot 33 in the end of the adjusting member 32 and is pivotally connected to member 32 by means of a pivot pin 47. 20 Thus relative movement of members 27 and 32 will result in rocking the block 29 so as to direct the pads 43 and 44 either upwardly or downwardly. The extra length of slot 31 provides for such relative adjustment of 25 members 27 and 32. Also members 27 and 32 may be adjusted in unison forward and backwardly upon cross-bar 21 to retract or project the head-rest pads. Either or both of said adjustments may be effected at one 30 operation whenever the bolt 36 is loosened. The two bolts 26 and 36 hold the members 21, 27, and 32 firmly in relative position one above the other and guide said members in their endwise adjustments, and serve to 35 readily clamp and release said members as may be required. The link connection between the members 32 and 29 facilitates positive adjustment of the pads 43 and 44 and a relatively wide range of adjustment 40 of the pads for a smaller relative adjustment of the members 27 and 32.

The plate or bracket 16 is provided with two projections 17 in which are perforations 46 and 47 to receive the shank 20. Said perforations 46 and 47 are in alignment vertically, and are beyond the face of the middle portion of the bracket 16, so that when both of the set screws 19 are tightened upon the shank 20 there is no tendency on the part of either of said set screws to distort or force the shank 20 out of alignment.

Where the head-rest apparatus is to be employed as a support for the head during operations upon the eye or for similar operations, it is important to insure a very strong and reliable support for the head rest. The plural spaced clamping action on the shank 20 also serves to better resist any strain put upon the clamping bolt 36 to readjust or clamp the head-rest.

The apparatus herein shown and described is capable of considerable modification without departing from the spirit of my invention.

What I claim is:

1. A head-rest apparatus comprising a shank, means to adjustably support said shank, a cross-bar mounted upon the upper end of said shank, and slotted longitudinally thereof, a pair of longitudinally slotted adjusting members mounted upon said cross-bar one above the other, a clamping and guide bolt attached to the upper of said adjusting member and riding in the slot of the lower adjusting member and in the slot 75 of said crossbar, a clamping and guide bolt threaded into said cross bar and riding in the slot of the upper adjusting member and in the slot of the lower adjusting member and adapted to be hand actuated to clamp 80 said adjusting members to said cross bar at one operation, a head-rest member pivotally connected directly to one of said adjusting members and indirectly through a link to the other of said adjusting members. 85

2. A head-rest apparatus comprising a shank, means to adjustably support said shank, a cross-bar mounted upon the upper end of said shank, a pair of adjusting members mounted upon said cross-bar one above 90 the other and adjustable endwise upon and relative to said cross-bar and also relative to each other, means to guide said adjusting members endwise relative to said cross-bar and relative to each other, means to hold 95 said adjusting members near opposite ends in contact with said cross-bar and with each other face to face, means to rigidly clamp both of said adjusting members to said cross-bar, a head-rest member pivotally attached 100 to one of said adjusting members, and indirectly pivotally connected through a link with the opposite of said adjusting members.

3. A head-rest apparatus comprising a shank, means to support said shank, a cross-bar mounted upon the upper end of said shank, a pair of adjusting members mounted upon said cross-bar one above the other and adjustable endwise upon and relative to said cross-bar and also relative to each other means to guide said adjusting members near opposite ends thereof endwise relative to said cross-bar and relative to each other, means to hold said adjusting members 110 near opposite ends in contact with said cross-bar and with each other, means to rigidly clamp both of said adjusting members to said cross-bar at one operation, a head rest member directly pivotally attached to one of said adjusting members and a link pivotally connected at one end to said head-rest member and at its opposite end to the opposite of said adjusting members. 115

In testimony whereof I have affixed my signature.

EUGENE BERNINGHAUS.
